UNITED STATES PATENT OFFICE.

HENRY C. MILLER, OF MILWAUKEE, WISCONSIN.

LOOSE-LEAF BINDER.

No. 848,671.

Specification of Letters Patent.

Patented April 2, 1907.

Application filed July 7, 1905. Serial No. 268,681.

To all whom it may concern:

Be it known that I, HENRY C. MILLER, of Milwaukee, Wisconsin, have invented a Loose-Leaf Binder, of which the following is a specification.

My invention relates to loose-leaf binders, and more particularly to the posts thereof, which join the binder-bars and complete the back of the binder.

10 In transfer-binders—that is, those binders which are used as reference-files for old sheets and in which the latter accumulate sometimes to a very large number—it requires a wide range of adjustability in the lengths of 15 the posts to enable the ledger to expand from an indefinitely small thickness to the thickness required, which is unlimited by anything but the ease of handling the ledger. Heretofore sectional posts have been devised 20 for this purpose—namely, posts made up in a plurality of joints of definite length, which could be successively added, thus expanding the back of the binder by intervals equal to the length of one post. These binders have, 25 however, proved unsatisfactory for the reason that they do not permit an even degree of adjustability which enables the back to be compressed to hold any number of sheets whatever. Posts have also been devised per- 30 mitting continuous adjustment in length; but these posts have the disadvantage of a narrow limitation between their shortest and greatest length. Means for adjusting the lengths of posts have also been used, which 35 involve the projection of the unused portion of the posts beyond one side of the binder, and this construction embodies the obvious disadvantage that the projections are in the way and are likely to strike against objects. 40 Besides, it prevents the binders from lying flat, and the projections of one binder prevent other binders from being placed evenly on top of it.

It is my object herein to provide a post for 45 loose-leaf binders in general, and especially for transfer-binders, which while admitting expansion to any desired amount may still have the property of a continuous adjustment in the length—that is, one not depending on 50 the length of the section and which will also avoid the difficulty of projecting posts at either side of the binder-cover.

I further design to provide a post having both sectional and continuous adjustments, 55 which said adjustments are carried out from opposite ends of the posts. In other words,

sections may be removed and replaced one at a time, and leaves may be removed and inserted without in any way interfering with the continuous-adjustment feature or involving an unnecessary amount of attachment and detachment.

I further design to provide an improved form of sectional post which shall avoid certain disadvantages of posts heretofore in use. In the old form, each post was provided with a male thread at one end and a female at the other, and midway a hole through the center of the post for the insertion of a tommy by which the sections could be unscrewed. Now supposing several sections to be joined and it was desired to remove only the upper one, the rotating of this one would cause one of the other joints to release instead of the joint desired, (it being impossible to hold the joint next below stationary on account of the sheets held by it,) and in consequence several sections would be removed instead of only one. In my invention this is avoided by having an independent screw fixed in each section and connecting it with the next section, and the screw in each section is covered by that next above it, so that it is possible to release only the upper section, and the sections below are maintained rigidly in position.

In my improved post I may further provide a tongue and slot between the sections, which causes each section to engage with the adjacent section and prevents them rotating relatively to one another.

A further improvement which I have in view is the formation of transverse slots or nicks in the free end of the sections to replace the transverse holes heretofore in use, in enabling the sections to be rotated by means of a screw-driver or of an ordinary coin, which is generally the most convenient tool for the purpose.

My improvements are best understood from the following description, taken in connection with the accompanying drawings, wherein I have shown several embodiments thereof.

In the drawings, Figure 1 is a perspective view of a loose-leaf binder constructed according to my invention. Fig. 2 is a partly-sectional and partly-elevational view of one post thereof, on an enlarged scale. Fig. 3 is a perspective view of one of the sections of the post as constructed in Figs. 1 and 2. Fig. 4 is a view similar to Fig. 2 of a post in

which the old form of sections are used. Fig. 5 is an elevation of a couple of sections of a modified form of post wherein the transverse notches are adapted for use in rotating the posts to screw them in or out. Fig. 6 is an elevation of a screw-driver for use in connection with the post shown in Figs. 1 and 2. Fig. 7 is a similar view of a turning implement for use in connection with the nut 10 shown in Fig. 4.

The binder comprises substantially a pair of covers A and B, each consisting of a rigid back bar 11 12 and a flap 13, united thereto by a flexible joint 14, of cloth or leather or like material, and a plurality of posts (ordinarily two in number) C, uniting the bars 11 12. While I do not limit myself to any construction of back bars, those herein shown are supposed to be of wood or like material, 15 having a canvas or leather covering 15. At the point where the post C is secured to the upper bar 11 the latter is bored through and hollowed out to receive the inner member 16 of the upper or continuous-adjustment section 17 of the post C, the member 16 having a flange 18, which is secured between the bar 11 and an inset piece 19, the latter being glued or otherwise fixed in a mortise 20 made in the bar 11 to receive it. Thus fixed the member 20 depends from the inner side of the back bar, as shown. This member is tubular, and its internal diameter is less at the top than at the bottom, the former being internally threaded to receive the threaded portion 21 of the adjusting-screw 22, which is 25 provided with a head 23, projecting above the end of the member 16, and which is prolonged to extend through the member 16 and has at its lower end a conical tip 24. The member 16 operates within the outer member 20 of the upper section 17 of the post C, this lower member being likewise tubular and fitting over the member 16, which is adjustable within it. The lower end of the member 16 is longitudinally slotted, as shown 30 at 26, so as to divide it radially into segments, which are somewhat flexible, each segment having on its lower end a heel 27, engaging frictionally the inner side of the member 25, and a toe or point 28, extending 35 inwardly and against which presses the conical tip 24 of the adjusting-screw 22. I prefer, also, to turn the upper edge of the member 25 inwardly, as shown at 29, whereby the heel 27 engages therewith on the full extension of the section and prevents the inner member 16 from accidentally coming out. The screw-head 23 is preferably sunk in a recess 30, which prevents it from projecting 40 above the cover and permits a coin to be inserted edgewise into the neck of the head to turn the same. The remainder of the post consists of a plurality of sections 31, which are all alike, and each is composed of a hollow bar- 45 rel having one end thereof (the upper end in

Fig. 2) provided with an internal annular flange 32. The opening is just large enough to receive the shank of a screw 33, the head 34 of the screw abutting on the inner edge of the flange. The opposite end of the barrel of the section 31 and also that of the outer member 25 of the upper section 17 is closed by an annular plug 35, which is internally screw-threaded, as shown at 36, Fig. 3, to engage with the threaded portion 37 of the screw 33. 50 Moreover, I prefer in some cases to provide, as shown, a tongue-and-groove connection consisting of a pair of small teats 38, projecting on one end of each section 31 and corresponding notches 39 on the other end, the teats 38 on one section fitting into the notches 39 on the adjacent section, so as to prevent the sections from rotating relatively to one another. It is not, however, essential 55 that this tongue - and - groove connection should be provided, as experience shows that when the screw 33 is drawn up tight friction is sufficient to keep the sections from rotating one upon the other. The last section of the post—that is, the lowest one in Fig. 2—is 60 fixed to the back bar 12 of the lower cover-section B in similar manner—to wit, by means of one of the screws 33 engaging the thread 36 of the plug 35 of the section. The screw 33 in this case passes through a hole in 65 a plate 40, which is set in a recess or mortise in the back bar in like manner to the block 19 in the upper back bar and may be secured thereto by means of screws 41 countersunk so as to permit the covering material 15 to 70 cover the plate, and the outer side of the back bar around the screw-head is conically recessed, as shown at 42, in like manner to the upper back bar. The method of operating the binder as thus constructed is as follows: Should it be desired to release the leaves sufficiently to extract one or more of them without disturbing the remaining leaves, it is only necessary to unscrew the adjustment-screw 22 sufficiently to allow the 75 two members 16 and 25 to slide freely one on the other, when the upper binder-cover may be raised and the sheets released, and, similarly, to clamp said leaves again the back bar 11 is depressed upon the leaves, and the screw 22 is then screwed in until the ends 28 of the segments in the lower end of the inner section 16 are forced apart by the conical tip 24 of the screw, so that the heels 27 thereof engage frictionally with the sides of the head 80 25. When the binder becomes expanded by the continual insertion of leaves until the upper section 17 is fully drawn out, then the binder is turned over and a screw-driver or coin inserted in the nick of the screw 33 on the back bar of the binder-cover, and the latter is unscrewed. Another section 31 may then be added to the post by inserting a screw-driver 51 (see Fig. 6) of sufficiently 85 small dimensions to enter the plug 35 and the 90

barrel of the section and rotating the screw 33 thereof, so as to cause it to engage with the plug 35 of the end section, when it is screwed up tight, and the binder-cover is 5 then secured in like manner to the end of the new section. This is done, as will be readily seen, without disturbing the adjustment of the upper section 17 and without removing any leaves from the binder nor requiring the 10 removal of any section of the post. If, on the other hand, it is desired to shorten the binder by a greater amount than the extension of the section 17, the screw 33 on the under binder-cover is in like manner removed, 15 as before, and then the aforesaid screw-driver 51 inserted through the barrel of the end section and the latter unscrewed, and so the sections may be removed successively as many as may be desired. It will be observed 20 that by this construction it is absolutely impossible for any section but the end section to be loosened.

In Fig. 4 I have shown how my invention may be applied to the old form of post-sections. The binder-covers and their bars 11 and 12 are unchanged, and so, also, is the inner member 16 of the upper section 17' of the post. (The screw 22 is removed in this figure.) The outer member 25' of this section 25 is, however, closed at the bottom and provided with a projecting screw-threaded boss 43. Each of the other sections 31' has a similar boss 44 on one end and an internal thread 45 on the other to receive the boss of 30 the adjacent section, as will be readily understood, and, further, this old form of section is provided with a transverse hole 46 at some point of its length for the insertion of a tommy-bar to rotate it. The end section 31' is 35 here shown as secured to the back bar 12 by a T-shaped nut 47, fitting over the boss 44 and having a pair of holes 48 at opposite ends of the diameter, into which are inserted the pins 49 of a turning implement 50, (see Fig. 40 7,) the rim of the nut 47 abutting against the outer margin of the plate 40. This old form has the disadvantage that it is necessary to use two tommy-bars—one in the hole 46 of the 45 next following section—in order to prevent the screw-threads from releasing at some point farther down on the post; but it still embodies my invention so far as the continued and unlimited adjustment of the binder is 50 concerned.

In Fig. 5 is shown a form of post comprising sections 31'', similar to those of Fig. 1, except that the independent screws 33 are replaced by screw-bosses 33' and the teats 38 60 are removed, the notches 39' being the same as the notches 39. In this case it is not necessary to use a screw-driver 51 to remove the separate sections, but they are removed by merely inserting a coin into the notches 65 39' on the end section and then rotating it.

This means of unscrewing the sections is superior to the holes 46, (shown in Fig. 4,) because the latter are always covered by the leaves mounted in the binder, and it is a matter of inconvenience to raise these leaves to 70 find the holes 46 and insert the tommy-bars thereinto.

The various elements of superiority in my improved post should be clear from the above description, and it will be understood, 75 of course, that certain mechanical changes may be made in the construction without interfering with the principle of the invention.

Having thus described my invention, what I claim as new, and desire to secure by Letters Patent, is—

1. In a loose-leaf binder, a rigid sectional post having means for continuously varying its length at one end, and means for adding sections at the other end thereof. 85

2. In a loose-leaf binder, a rigid sectional post comprising a plurality of sections joined together, one of said sections being composed of two members which telescope one within the other, and means for adjusting the extension of said telescoping section in combination with a binder-bar removably secured to one end of said post. 90

3. In a loose-leaf binder, a rigid sectional post comprising an extensible section secured 95 at one end to one cover of the binder and having means for adjusting its extension, and a plurality of interchangeable sections adapted to be secured to the free end of said extensible section and to each other in combination with a binder-bar removably securable to the end of said post opposite said extensible section. 100

4. In a loose-leaf binder, a post-section comprising a barrel having an internal thread 105 at one end and a screw fitting said internal thread and rotating loosely in said barrel, the thread of said screw projecting when in use from the opposite end so as to engage the internal thread of the next section. 110

5. In a sectional post for loose-leaf binders, a post-section having a transverse notch at one end thereof, and a transverse projection at the other end adapted to fit in the notch of the adjacent section; said notch and 115 projection being shaped to permit the projection on one section to enter the notch on another section when the two are brought together endwise, in combination with means on said section for securing it to the adjacent 120 section.

6. A sectional post for loose-leaf binders comprising a plurality of sections having a device operated from one end thereof engaging it to the section abutting on the other 125 end, said device being covered by the section abutting on the first end.

7. A loose-leaf binder comprising in combination with a pair of back bars, an extensible section secured at its end to one of said 130

bars, and comprising telescoping members, means for adjusting the extension of said section from the outer side of the bar to which it is attached, a plurality of interchangeable sections one or more of which is secured to the free end of said extensible section and each of which comprises a barrel having an internal thread at one end and a screw loosely rotating in said barrel and projecting when in use from the other end, said screw engaging the internal thread of any of said sections; and a screw set in the opposite back bar and rotating in a hole therein, the thread thereof projecting from the inner side of said back bar and engaging the internal thread of the end section of the post.

8. In a sectional post for loose-leaf binders, a post-section comprising a hollow barrel having an internal flange 32 around one end, a screw 33 having its shank passing through the opening in said flange and its head abutting thereagainst, and an internally-screwed plug 35 secured in the opening of the other end of said barrel, said barrel having on one end a projecting part and on the other end a depressed part adapted to receive the projecting part of the adjacent section.

ting thereagainst, and an internally-screw-threaded plug 35 secured in the opening of the other end of said barrel.

9. In a sectional post for loose-leaf binders, a post-section comprising a hollow barrel having an internal flange 32 around one end, a screw 33 having its shank passing through the opening in said flange and its head abutting thereagainst, and an internally-screwed plug 35 secured in the opening of the other end of said barrel, said barrel having on one end a projecting part and on the other end a depressed part adapted to receive the projecting part of the adjacent section.

In testimony whereof I have hereunto set my hand this 5th day of July, 1905.

HENRY C. MILLER.

In presence of—

R. E. GEHRKE,

ADOLPH G. LOTTAR.
